CLAIM

I claim the ornamental design for a hitch holder, as shown and described.

DESCRIPTION

FIG. 1 is a front perspective view of a hitch holder showing my new design;

FIG. 2 is a rear perspective view thereof;

FIG. 3 is a rear elevation view thereof;

FIG. 4 is a front elevation view thereof;

FIG. 5 is a top plan view thereof;

FIG. 6 is a bottom plan view thereof; and,

FIG. 7 is a left side elevation view thereof.

The broken lines in the drawings depict portions of the hitch holder that form no part of the claimed design.
